MOUNT

Carroll N. Cross, Middleboro, Mass.

Application April 2, 1942, Serial No. 437,452

2 Claims. (Cl. 40—152.1)

This invention relates to display mounts of the kind adapted to support and display photographs, pictures or other indicia.

More particularly, the invention relates to a display mount having a mount supporting easel adapted to support the mount in display position.

In my Patent No. 2,240,209 I have disclosed a display mount having a supporting easel which may be folded into the plane of the back of the mount so as to occupy little space and permit a large number of mounts to be stacked upon each other with ease and without danger of warping. The mount disclosed in my prior patent also includes a locking tongue for holding the mount supporting easel in open position and the tongue shown in that patent is formed from the body of the easel.

It is the primary object of this invention to provide a mount of the general character shown in my previous patent but which embodies a construction wherein the easel locking tongue is formed in an intermediate board. This improved construction preserves substantially the entire surface area of the mount supporting easel thereby adding greatly to its strength and providing additional safeguards against warping which has heretofore been the primary objection to display mounts constructed of relatively light-weight flexible stock such as cardboard.

Further objects and advantages of the invention will become apparent as the description of an illustrative embodiment thereof is read in connection with the drawing forming a part hereof. In the drawing like reference numerals indicate like parts and

Figure 1 illustrates the face board forming a part of the mount;

Figure 2 illustrates the intermediate board forming a part of the mount;

Figure 3 illustrates the back board forming a part of the mount; and

Figure 4 is a medial longitudinal sectional view of the mount showing the same in display position.

In the preferred construction the mount body consists of a plurality of boards, herein illustrated as consisting of a face board 10, an intermediate or second board 12, and a back board 14, all of which may be substantially coextensive. The face board 10, the intermediate or second board 12, and the back board 14 are joined together to form a unitary structure. Insofar as this invention is concerned, the three boards constituting the mount may be joined in any suitable manner but preferably they are joined by means

of a flexible decorative binding material 16 which extends over the entire facial surface of the face board 10 and around the marginal edges of the three boards. The marginal edges of the binding material 16 are folded against the rear surface of the back board. The exposed marginal edges of the binding material 16 are preferably concealed by a second piece of binding material 18 which is attached to the rear surface of the back board 10 and overlaps the exposed edges of the facing material 16. The binding materials 16 and 18 are preferably attached to the adjacent surfaces of the mount by means of gluing the same throughout their entire surface area.

15 The face board 10 has provided therein a picture-display window 22 through which a picture or other indicia may be viewed. The intermediate board 12 has formed therein a tongue 24 which has a free end adapted to engage an easel 20 for retaining the mount in display position. Herein, for purpose of illustration, the free end of the tongue is shown as being disposed near the bottom of the board. The tongue 24 is provided at its other end with one or more transverse score lines 26 about which it may swing into an angular position.

20 The back board 14 has provided therein a mount supporting easel 28 which has its free end adapted to rest against a supporting surface when the same is opened to mount supporting position. Herein, for purpose of illustration, the free end of the easel is shown as being disposed near the bottom of the board. The opposite end of the easel 28 is provided with one or more transverse score lines 30 about which the same may swing into an angular position. The easel 28 is also provided with means for engaging the free end of the locking tongue 24 and herein that means is illustrated as comprising an aperture 32 into 25 which the reduced shouldered end 34 of locking tongue 24 may pass. The locking tongue 24 and the easel 28 may be attached to their respective boards in any way so long as they are correlated to permit inter-engagement of their respective 30 engaging portions 32—34.

In the preferred construction it will be seen that the bottom of the picture-display window 22 lies at least slightly above the score lines 26 at the upper end of the locking tongue 24. By arranging the proportions of the several parts in this manner, the intermediate board 12 presents a continuous surface 36 affording substantial support for a picture or the like.

Herein the face board 10 forms a decorative 35 frame for a picture in the mount. However, the

face board may be omitted from the combination without effecting the function and advantages of the easel and locking tongue arrangement. A picture 40 may be assembled with the mount during the manufacture thereof or any conventional picture-inserting opening may be provided for the purpose of inserting and removing pictures from the mount enclosure.

The invention has been described herein with respect to a single embodiment thereof but the advantages of the construction may be achieved in other forms and it is therefore my intention that the invention be not limited other than by the limitations appearing in the following claims.

What I claim is:

1. In a picture mount or the like constructed of light-weight flexible stock adapted to support a picture in display position, a back board, an easel formed in said back board and being hinged thereto for angular movement into and out of mount-supporting position, a cut-out slot in said easel, a second board lying in contact with the face of said back board, a face board overlying said second board, means joining said boards together to form a unitary mount structure, a picture display window in said face board, an easel locking tongue formed in the lower portion of said second board under said easel, said tongue having a free end and a base that is integral with said second board, a score line extending across the base of said tongue at a point below the bottom edge of said display window, the free end

of said tongue being adapted to engage the slot in said easel in mount-supporting position and said tongue being adapted to lie parallel to and between said face board and the easel in said back board when said parts are folded in non-supporting position.

2. In a picture mount or the like constructed of light-weight flexible stock adapted to support a picture in display position, a back board, an easel formed in said back board and being hinged thereto for angular movement into and out of mount-supporting position, a cut-out slot in said easel, a second board lying in contact with the face of said back board, a face board overlying said second board, means joining said boards together to form a unitary mount structure, a picture display window in said face board, an easel locking tongue under said easel, said tongue having a free downwardly extending end and a base at its upper end that is integral with said second board, a score line extending across the base of said tongue at a point below the bottom edge of said display window and in a direction substantially parallel thereto, the free end of said tongue being adapted to engage the slot in said easel in mount-supporting position and said tongue being adapted to lie parallel to and between said face board and the easel in said back board when said parts are folded in non-supporting position.

CARROLL N. CROSS.
